UNITED STATES PATENT OFFICE.

JOHN M. TRAVIS, OF ST. LOUIS, MISSOURI.

DESIGN FOR A DISPENSING-FONT.

40,985.

Specification for Design.

Patented Nov. 8, 1910.

Application filed September 10, 1910. Serial No. 581,455. Term of patent 7 years.

To all whom it may concern:

Be it known that I, JOHN M. TRAVIS, a citizen of the United States, and a resident of the city of St. Louis and State of Missouri, have invented a new, original, and ornamental Design for Dispensing-Fonts, of which the following is a specification.

In the accompanying drawing, which forms a part of this specification, Figure 1. is a side elevation of a dispensing font embodying my design; and, Fig. 2. is a front elevation thereof.

What I claim is:

The ornamental design for a dispensing font as shown.

JOHN M. TRAVIS.
